UNITED STATES PATENT OFFICE

99,690

DESIGN FOR A DISPLAY CASE

Thomas E. Wharton, Fairfield, Conn.

Application August 3, 1935, Serial No. 57,931

Term of patent 14 years

To all whom it may concern:

Be it known that I, Thomas E. Wharton, a citizen of the United States, residing at Fairfield, county of Fairfield, State of Connecticut, have invented a new, original, and ornamental Design for a Display Case, of which the following is a specification, reference being had to the accompanying drawing, forming part thereof.

In the drawing:

Fig. 1 is a perspective view of the display case illustrating my design.

Fig. 2 is an end view of the same case.

The case comprises a body having an upwardly and rearwardly inclined article displaying sur-

face which is separated into trays of a size suitable for the displaying of particular assortments of articles. At the back of the case is a substantially upright holder separated into frames or panels. The characteristic feature of the design is the alignment of each of these panels with a group of the article receiving trays, each panel being arranged to receive a pictorial illustration of the use of the particular articles in the associated tray or group of trays.

I claim:

The ornamental design for a display case, as shown and described.

THOMAS E. WHARTON.
